UNITED STATES PATENT OFFICE.

JERVIS R. HARBECK, OF DETROIT, MICHIGAN, ASSIGNOR, BY MESNE ASSIGNMENTS, TO DETROIT CAN COMPANY, OF DETROIT, MICHIGAN, A CORPORATION OF NEW JERSEY.

MACHINE FOR INTERNALLY COATING TUBES.

1,051,103.

Specification of Letters Patent. Patented Jan. 21, 1913.

Application filed February 2, 1910. Serial No. 541,636.

To all whom it may concern:

Be it known that I, JERVIS R. HARBECK, a citizen of the United States of America, residing at Detroit, in the county of Wayne 5 and State of Michigan, have invented certain new and useful Improvements in Machines for Internally Coating Tubes, of which the following is a specification, reference being had therein to the accompanying drawings.

The invention relates to the manufacture of tubes from spiral wrappings of paper or strips of paper or other flexible sheet material, and it is the object of the present invention to provide means—constituting a part of the tube-forming apparatus—for coating the inner surface of the tubes with a liquid enamel.

Heretofore, paper tubes of the character described have been internally coated during the process of manufacture by the application of the coating substance to the inner face of the paper strip before it is wound upon the mandrel. Inasmuch, however, as the usual process of forming the tube is to wind the strip by revolving it over a stationary mandrel, the coating material employed must be restricted to substances of a lubricating character, and any material of an adhesive nature will prevent a proper operation of the machine. With my improved construction, the tube may be enamelled with any material desired, whether of an adhesive nature or otherwise, and without interfering in any way with the successful operation of the winding machine.

In the drawings, Figure 1 is a plan view of a tube forming machine to which my improvements are applied; Fig. 2 is an enlarged cross section through the mandrel, showing the enamel coating appliance; Fig. 3 is a longitudinal section through the mandrel, showing the parts illustrated in Fig. 2, and also the means for supplying the liquid enamel and maintaining a constant level.

The machine for winding the paper strips and forming the tubes may be of any suitable construction of the general character described, but as shown in detail in Fig. 1 A is a suitable frame, upon which is mounted the stationary mandrel B. C C' are paper strips fed over the mandrel at the proper angles to produce a spiral wrapping, one of the strips being arranged to overlap the joint of the other. D is a drive belt, which

is wrapped about the mandrel and the tube in process of formation thereon, and serves to rotate and longitudinally advance said tube at the rate at which it is being wound. E E' are pulleys for the belt D on opposite sides of the mandrel, one or both of which are driven by suitable mechanism (not shown). This apparatus, which is merely illustrated and described in its more essential and characteristic features, is one which will continuously form paper tubes and deliver the same from the rear end of the mandrel. During movement over the mandrel, the inner surface of the tube is in frictional contact therewith; and, consequently, as has been already stated, any material of an adhesive nature between the paper and the mandrel, particularly at the point of winding, would interfere with its successful operation. With my improvement, the enamel is applied to the inner surface of the tube after the winding, and preferably at the rear end of the mandrel upon which it is wound. To this end, a chamber F is formed within the mandrel, which is filled with the enameling material, and is apertured, as at G, for the passage of the enamel into contact with the inner surface of the tube. I preferably also employ a roll H, which is arranged longitudinally of the mandrel in the aperture G and has the outer portion of its periphery arranged to contact with the inner face of the tube, while the inner portion is immersed in the fluid in the chamber F. Thus, as the tube rotates and is advanced over the roll H, it is coated with the enamel, and the rotation of the roll not only distributes the liquid over the surface but also reduces the frictional resistance.

To maintain the enamel in liquid form and the proper consistency, it must be heated, which is preferably accomplished by heaters, such as the steam pipes I passing through the chamber F. It is also essential to renew the supply of liquid and to maintain a substantially constant level, and this is done by extending the supply pipe J through from the forward end of the mandrel into the compartment F therein, while outside of the mandrel a suitable device is provided for maintaining a constant level, such as the inverted container K having its lower end immersed in a receptacle L.

With the construction as described, the paper tubes delivered from the winding

mechanism are thoroughly coated with the enamel upon passing over the roll H, and are then delivered from the machine.

What I claim as my invention is,—

5 1. The combination with a mandrel and means for winding a paper strip thereon to form a tube, of a chamber within said mandrel for a liquid, and a distributing roll located in an aperture in the periphery of said 10 mandrel and immersed in the liquid in said chamber for applying the liquid to the inner face of the tube.

2. In a machine for rolling spiral paper tubes, in combination with a hollow mandrel provided with a slotted opening thereto, a roller journaled in said opening in position of axial parallelism with the mandrel adapted to transfer from within said 15 mandrel through said opening a coating of cement and apply the same to the inner surface of the tube forming on said mandrel.

20 3. In combination with a hollow tube-forming mandrel having an aperture cut therein, a roller rotatably journaled in said

aperture eccentrically to the axis of the 25 mandrel, and means for maintaining in the mandrel a constant level of fluid, whereby, as the roller is rotated and engages peripherally the top surface of the fluid, the quantity thereby removed therefrom to the inside of the tube may be kept uniform.

4. In a machine for rolling spiral paper tubes, in combination with a slotted mandrel member, a roller member rotatably supported in the slotted portion, adapted to 30 peripherally engage the surface of a supply of fluid within the mandrel, and by its further rotation to transfer a desired quantity of the same to the outside of the mandrel, there to become adherent to fibrous material 40 passing thereover.

In testimony whereof I affix my signature in presence of two witnesses.

JERVIS R. HARBECK.
